W. C. BROUGHTON,
FIREPROOF DOOR,
APPLICATION FILED JULY 5, 1921.

1,416,943.

Patented May 23, 1922.

UNITED STATES PATENT OFFICE.

WALTER C. BROUGHTON, OF KANSAS CITY, MISSOURI.

FIREPROOF DOOR.

1,416,943.

Specification of Letters Patent. Patented May 23, 1922.

Application filed July 5, 1921. Serial No. 432,377.

To all whom it may concern:

Be it known that I, WALTER C. BROUGHTON, a citizen of the United States, residing at Kansas City, in the county of Jackson and State of Missouri, have invented certain new and useful Improvements in Fireproof Doors, of which the following is a specification.

My invention relates to fire proof doors for garages, and other buildings, and one feature of the invention resides in the novel construction of the doors which may be folded to occupy but little space when in open position.

Other features will hereinafter appear and in order that the invention may be fully understood, reference will now be had to the accompanying drawings, in which:

Fig. 1 is a front elevation of a garage equipped with the doors.

Fig. 2 is an enlarged horizontal broken section taken on line II—II of Fig. 1.

Fig. 3 is a vertical sectional view of one of the door panels before being completely filled with concrete or the like, said panel being in a reverse position to that disclosed by Figs. 1 and 2.

Fig. 4 is an enlarged fragmentary cross section showing one of the hinges for foldably connecting certain panels of the doors together.

Fig. 5 is a broken vertical section on line V—V of Fig. 3 with the door panel filled with concrete.

Fig. 6 is a fragmentary section showing one of the hinges whereby the doors are connected to the front panels of the garage.

Referring now in detail to the parts disclosed by the drawings, 2 designates a garage embodying corner columns 4 and front and side panels 6 and 8, respectively.

10 designates the doors at the front of the garage, two doors being employed and each door in the present instance consisting of two panels 12, which are foldably connected so that when opened to the position disclosed by dotted lines, Fig. 2, they may be adjusted to occupy but little space close to the inner sides of the side panels 8.

In order that the door panels 12 may be made as light and strong as possible, I construct each as follows: 14 designates a rectangular frame made, preferably, of angle irons and filled with concrete or similar material 16. In addition to the frame 14 the

concrete is reinforced with longitudinal rods 18, wires 19, bolts 20 and nuts 22, all of which are placed in position before the frame 14 is filled with the concrete 16.

When the bolts 20 are placed in position 60 they are firmly secured to the angle irons of the frame 14 by nuts 24, so that they cannot work loose in the concrete. The wires 19 are wrapped around the rods 18 and a number of wires are extended around the 65 nuts 22 after which the same are tightened upon the bolts 20 to take up slack in said wires 19 and hold the same taut. Short wires 26 are wrapped around the bolts 20 to hold that portion of the cement or concrete between the two sidemost rods 18 and the adjacent sides of the frame 14.

The two panels 12 constituting each door 10 are connected by hinges 28 which are firmly secured to the adjacent sides of the 75 frame 14 by bolts 30 and nuts 32, which latter like the nuts 24 are provided to hold the bolts firmly in position in the respective frames 14. The bolts 30 are further held in place by nuts 34 which like the nuts 32 80 may be employed to tension some of the wires 19.

A number of angle irons forming part of the frames 14 are so positioned that their front sides 36 overlap the joints 37 between 85 the panels 12 as disclosed by Figs. 1 and 2, to exclude dust, rain, etc., while the two sidemost angle bars 35 are placed in reverse position to the others to close the joints 38 between the panels 6 and the adjacent 90 sides of the doors 10 and, also, to provide substantial means to which hinges 40 may be secured. The uppermost angle irons are arranged with one side 41 turned upwardly to close the joint between the upper margins of the doors 10 and the lintel 43 against the rear side of which the sides 41 abut when the doors 10 are closed.

The hinges 40 support the doors 10 and in turn are supported by bolts 42 and nuts 100 44, secured to plates 46 which are secured to the panels 6 with bolts and nuts similar to the manner in which the hinge 28 is connected to the panel 12, Fig. 4.

From the foregoing description it is apparent that I have produced foldably fireproof doors embodying the advantages above pointed out, and while I have shown and described the preferred construction, combination and arrangement of parts, I reserve 110

the right to make such changes as properly fall within the spirit and scope of the claims.

Having thus described my invention, what I claim and desire to secure by Letters Patent, is:

1. A door structure consisting of a rectangular metallic frame, bolts spaced apart and extending into said frame, nuts threaded upon said bolts, wires connected to said nuts and drawn taut thereby, and suitable material filling said frame.
- 10 2. A door structure consisting of a rectangular metallic frame, bolts spaced apart and extending into said frame, nuts threaded upon said bolts to firmly hold them in position in the frame, other nuts threaded upon the bolts, reinforcing rods arranged within the frame, wires connected to said 15 rods and the last-mentioned nuts whereby they are drawn taut, and suitable material filling said frame.
- 20 3. A door consisting of a plurality of

panels, each panel consisting of a metallic frame, bolts spaced apart and extending into said frame, nuts threaded upon said bolts, wires connected to said nuts and drawn taut thereby, fire proof material filling said frame, a plurality of hinges, and bolts and nuts connecting said hinges to the frames of the panels so that the latter may fold against each other.

4. In a door structure, a rectangular metallic frame, bolts spaced apart and extending into said frame, nuts threaded upon said bolts and engaging the inner surface of the frame to secure said bolts firmly in place, other nuts threaded upon the bolts, and flexible reinforcing means drawn taut within the frame by the last-mentioned nuts.

In testimony whereof I affix my signature, in the presence of two witnesses.

WALTER C. BROUGHTON.
